FOLDABLE DISPLAY STAND

George Patton, Jr., Barrington, R.I., assignor to Rexall Drug and Chemical Company, Los Angeles, Calif., a corporation of Delaware

Filed Mar. 10, 1965, Ser. No. 84,190

Term of patent 14 years

(Cl. D80—9)

FIG. 1

FIG. 8

FIG. 2

FIG. 10

FIG. 3

FIG. 4

FIG. 5

FIG. 7

FIG. 6

FIG. 9

FIGURE 1 is a perspective view of a foldable display stand showing my new design, wherein the stand is illustrated in its closed covered position;

I claim:

The ornamental design for a foldable display stand, substantially as shown and described.
